Primary Examiner — Cathron Brooks*Assistant Examiner* — Ian Whitmore(74) Attorney, Agent, or Firm — Harness, Dickey & Pierce(57) CLAIM

The ornamental design for a display screen or portion thereof with graphical user interface, as shown and described.

DESCRIPTION

The FIGURE is a front view of a display screen or portion thereof with graphical user interface showing my new design. The broken lines illustrate the environment of a display screen or portion thereof as well as portions of the graphical user interface, and form no part of the claimed design.
